UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SHOW-CASE LIGHTING FIXTURE.

Application filed December 11, 1925. Serial No. 74,702.

My invention relates to show case lighting fixtures.

One of the objects of my invention is to provide a show case lighting fixture which 5 can be readily installed and wired.

A further object of my invention is to provide such a fixture which will be simple and compact in construction and durable and efficient in use.

10 A further object of my invention will appear from the description and claims.

In the drawings in which my invention is illustrated—

Figure 1 shows a sectional view through 15 the upper front corner of a show case showing the end of the show case lighting fixture;

Fig. 2 is a view from the right of Fig. 1;

Fig. 3 is a section substantially on the line 20 3—3 of Fig. 8, parts being broken away;

Fig. 4 is a section on the line 4—4 of Fig. 3;

Fig. 5 is a section on the line 5—5 of Fig. 3;

Fig. 6 is a section on the line 6—6 of Fig. 3;

Fig. 7 is a section on the line 7—7 of Fig. 6; and

Fig. 8 is a section on the line 8—8 of 30 Fig. 3.

Referring now to the drawings in detail, the construction shown therein comprises an elongated sheet metal casing 10 positioned in the upper front corner of the show case 11

35 and open on its lower inner side to permit the insertion of the lamps and to allow the necessary illumination of the articles in the show case, a pair of combined wiring base and contact members 12, one at each end of

40 the elongated casing and located within the casing, an external wiring base 13 located at the end of the elongated casing 10 and provided with wiring terminals for the connection of the feed wires and a detachable

45 socket member 14 into which the lamp is inserted.

The inner surface of the casing may be a reflecting surface in order to increase the illumination within the show case. Each wiring terminal on the outside wiring base 50 comprises a binding plate 15, secured to the insulating base by means of a screw 16, and a binding screw 17 threaded into this binding plate. The insulating base 18, on which the binding terminals are mounted is provided

with an aperture 19 in its upper portion for the passage of the feed wires 20 to the binding screws. An insulating cover 21 is provided to cover the feed wires lying in the channels 22, and the binding terminals. A 60 nipple or bushing 23 is provided to receive the insulating covering 24 of the feed wires and this nipple is secured to a metal plate 25 which is secured on the insulating base by means of screws 26. The lower one of 65 these screws 26 also serves to hold the insulating cover 21 in place.

Each of the wiring base and contact devices mounted inside of the elongated casing comprises an insulating base 27, suitably recessed to receive the yielding contact members 28 and the wiring terminals 29. Each one of the spring contact members 28, is electrically connected with one of the binding terminal members by means of a screw 30 which also serves to hold the contact and wiring terminal in place on the insulating base. Each screw 30, is threaded into a clamping plate 31, which engages the base of the spring contact. Each of the two 70 clamping plates 31, is electrically connected with one of the binding plates 15, on the outside wiring base by means of a long screw 32 (Fig. 7) which also serves to hold the outside wiring base in position at the end of 75 the casing. Each of the wiring terminals on the inside wiring base at one end of the casing is electrically connected with one of the binding terminals on the inside base at the other end of the casing by means of a wire 80 33, (Fig. 3) the upper end of which is inserted and soldered in the loop portion 34, of the binding terminal. An insulating cover 35, and metal cap 36, are provided for covering the wiring terminals 29, and closing the 85 end of the casing. The cover 35 and cap 36 are held on the base 27, by means of screws 37, (Fig. 3).

The detachable receptacle member 14, comprises an insulating base 38, lamp engaging contacts 39 and 40, and contact engaging blades 41 for engaging the spring contacts 28 on the insulating base 27. These contact blades 41, are connected, respectively, with the shell and center lamp contacts 39 and 40, by means of screws 42.

The circuit is from one of the feed wires 20, through one of the binding terminals 15, on the outside base, the screw 32, connecting the outside base with the inside base, the 110

spring contact 28, contact blade 41, screw 42, center contact 40, lamp, shell contact 39, screw 42, contact blade 41, spring contact 28, and screw 32 to the binding plate 15 for the 5 other feed wire. The wires 33 lying in the upper portion of the elongated casing serve to carry current from the binding terminals 29 on the insulating base at one end to the binding terminals 29 to the insulating base at 10 the other end.

While I have shown but one form of my invention, it is to be understood that I do not desire to limit myself to this particular construction since many changes and modifications may be made therein without departure from the scope of the following claims. 15

I claim:

1. A show case lighting fixture comprising an elongated open-sided casing for extending 20 alongside of the show case, two wiring base and contact devices, one secured in each end of each casing, conductor wires extending between and secured to said wiring bases, each wiring base having contacts thereon for 25 quick detachable engagement with the contacts on a lamp receptacle member, a wiring base for the supply wires mounted outside said casing and in alignment therewith, and means for electrically connecting the wiring 30 terminals on the outside wiring base with the wiring terminals on one of the inside wiring bases.

2. A show case lighting fixture comprising an elongated open-sided casing for extending 35 alongside of the show case, two wiring base and contact devices, one secured in each end of each casing, conductor wires extending between and secured to said wiring bases,

each wiring base having contacts thereon for quick detachable engagement with the contacts on a lamp receptacle member, a wiring base for the supply wires mounted outside said casing and in alignment therewith, and common means for electrically connecting the wire terminals on the outside wiring 45 base with the wiring terminals on one of the inside wiring bases, and for mechanically securing said outside wiring base in place at the end of the casing.

3. A show case lighting fixture construction comprising an elongated open-sided casing for extending along the edge of the show case, a wiring base secured in said casing at one end thereof, a cap for said casing covering the end of the wiring base, wiring terminals mounted on said base on the side adjacent the cap, contact members having base portions mounted on the other side of the wiring base, a receptacle member provided with lamp engaging contacts and having contact blades for quick detachable engagement with the contacts on the wiring base, a wiring base for the main feed wires mounted outside the casing adjacent the cap and in line with the casing, binding plates on said outside wiring base on the side adjacent the cap, and screws extending through the inside wiring base and threaded into said binding plate for securing said outside wiring base against the end of said casing, said screws being electrically connected with the wiring terminals and contacts on the inside wiring base.

In witness whereof, I have hereunto subscribed my name.

REUBEN B. BENJAMIN.
